LAPEL ORNAMENT

Ivan Bloch, Hartsdale, N. Y.

Application February 28, 1950, Serial No. 8,208

Term of patent 3½ years

(Cl. D45—19)

To all whom it may concern:

Be it known that I, Ivan Bloch, a citizen of the United States, residing at Hartsdale, in the county of Westchester and State of New York, have invented a new, original, and ornamental Design for a Lapel Ornament, of which the following is a specification, reference being had to the accompanying drawing, forming part thereof.

In the drawing

Fig. 1 is a top plan view of a lapel ornament, showing my new design;

Fig. 2 is a bottom plan view thereof; and
Fig. 3 is a bottom edge view thereof.

I claim:

The ornamental design for a lapel ornament, substantially as shown.

IVAN BLOCH.
